Patented Mar. 13, 1962

192,389

COMBINATION DISPENSING BOTTLE AND TOY

Eric De Kolb, New York, N.Y., assignor to The Fuller Brush Company, East Hartford, Conn., a corporation of Connecticut

Filed July 18, 1960, Ser. No. 61,401

Term of patent 14 years

(Cl. D58—9)

FIG.1

FIG.4

FIG. 1 is a front elevational view of a combination dispensing bottle and toy, showing my new design;

FIG. 2 is a side elevational view thereof;

FIG. 3 is a rear elevational view thereof; and

FIG. 4 is a top perspective view of the hat portion thereof, the body portion being omitted for convenience of illustration.

The side not shown is substantially the same as the side shown.

I claim:

The ornamental design for a combination dispensing bottle and toy, as shown and described.
